UNITED STATES PATENT OFFICE.

CHARLES C. ALLEN AND CHARLES H. BUSCH, OF NEBRASKA CITY, NEBRASKA, ASSIGNEES TO THE WILSON RE-ENFORCED CONCRETE CO., OF NEBRASKA CITY, NEBRASKA, A CORPORATION OF NEBRASKA.

REINFORCED-CONCRETE SECTIONAL PIPE AND CULVERT.

1,082,723.

Specification of Letters Patent.

Patented Dec. 30, 1913.

Application filed March 9, 1912. Serial No. 682,693.

To all whom it may concern:

Be it known that we, CHARLES C. ALLEN and CHARLES H. BUSCH, citizens of the United States, residing at Nebraska City, in the county of Otoe and State of Nebraska, have invented new and useful Improvements in Reinforced-Concrete Sectional Pipes and Culverts, of which the following is a specification.

10 This invention relates to conduits or culverts of the sectional type and made of reinforced concrete, and the primary object of the same is to provide means for effectively grouting or sealing the joints between the 15 coterminous ends of the sections of a strong and durable character and protected or guaranteed against blow-outs from inner or outer pressure and also permitting the formation of an inner flush joint so that the interior 20 portions of the connected pipe sections or culverts may be free of the least obstruction or roughness at their points of jointure.

A further object of the invention is to provide reinforced concrete pipe or culvert sections with inner and outer grouting channels to permit a pipe line to be laid in water and the application of grout to the inner channel from the top in a perfect manner 30 and also to provide for a perfect joint of the two channels and the sections.

A still further object of the invention is to provide reinforced concrete pipes or culvert sections having inner and outer grouting channels which may be filled from the top of the sections and also formed with clencher or anchor channels for holding the grouting in place, both in the inner and outer channels, and producing a more reliable joint and means for positively preventing the displacement of the grouting when run into and through the channels at the joined ends of the sections.

With these and other objects and advantages in view the invention consists in the construction and arrangement of the several parts which will be more fully hereinafter described and claimed.

In the drawing: Figure 1 is a perspective view of a pipe or culvert section embodying the features of the invention. Fig. 2 is a sectional elevation of two pipe or culvert sections with ends joined and particularly illustrating the advantages of the channels

and anchor or clencher grooves. Fig. 3 is an end elevation of one of the pipe or culvert sections.

The numeral 5 designates a pipe or culvert section or conduit formed of any suitable material, such as concrete, and preferably reinforced by longitudinally extending strengthening members or draw-bars 6 embedded therein and having their opposite ends so disposed as to project beyond the ends of each section and overlapped with similar devices of contiguous sections for the purpose of receiving coupling means of any suitable character. The projecting terminals of the draw-bars, which in the present instance are looped, will be accessible by the structure shown or by any other preferred means; the use of these draw-bars in connecting pipe sections of reinforced concrete being well known in the art and readily understood. The opposite ends of each section 5 are formed with segmental flanges 7 and 8, the flange 7 having its inner edge coinciding with the inner surface of the section and its outer edge terminating at a distance inwardly from the outer surface of the section, and the flange 8 being conversely arranged and having its inner edge terminating at a distance outwardly from the inner surface or periphery of the pipe section and its outer edge coincident with the outer surface of the section. Between the outer edge of the flange 7 and the outer surface of the pipe section an anchor or clencher channel or groove 9 is formed, and between the inner edge of the flange 8 and the inner surface or periphery of the pipe section a similar anchor or clencher groove 10 is provided, the grooves 9 and 10 having communication with each other through the medium of oblique cross-channels 11 at diametrically opposite points and about in alignment with the horizontal diameter of the pipe section.

Between the inner edge of the flange 8 and the inner periphery of the pipe section, an inner channel 12 is produced, from which the groove 10 may be said to recede; and between the outer edge of the flange 7 and the outer surface or periphery of the pipe section a channel 13 is provided from which the groove 9 recedes. In other words, the anchor or grouting grooves 9 and 10 open into or have communication with the channels 12 and 13, and the latter are in communication

through the downwardly inclined cross-channels 11.

In the operation of laying the pipe or culvert sections, a section is placed adjacent to the end of another section already laid and the terminals of the draw bars 6 are connected or locked. The joint is sealed by pouring grout or plastic concrete into the upper contiguous channels 13 and from the latter the grout or concrete runs into the grooves 9 and also flows downwardly through the cross-channels 11 into the lower channels 12 and grooves 10, the grouting or plastic concrete being applied in such quantity until all of the channels and grooves are filled and the joint sealed, the grouting or concrete being given a finished surface by the use of suitable tools at the upper portions of the joined sections or where the channels 13 are formed and unite. It will be observed that there will be no obstruction to the downward flow of the grouting or concrete material in view of the downward inclination of the cross-channels 11. When the grouting or plastic cement has been applied as just explained it will be anchored or clenched through the medium of the keys formed therein by the grooves 9 and 10, and the grouting when hardened will be reliably held in place both in the inner and outer channels, and blowing-out of the grouting by inner or outer pressure is prevented. The cross-channels 11 also afford means for closing the inner united channels 12 by gravitation of the grouting or plastic concrete, and through the construction specified the pipe

sections may be laid in water and the inner channels 12 grouted or filled with plastic concrete from the top of the united sections in a perfect manner and a positive bond between the two channels and pipe sections is provided.

What is claimed as new is:

In a sectional conduit, the combination of abutting sections having the opposite ends formed with segmental flanges which are less in thickness than the body of the sections and the one flange having its inner edge coinciding with the inner surface of the section and the remaining flange having its outer edge coinciding with the outer surface of the section to provide outer and inner channels formed in the upper and lower portions of the adjacent ends of the sections, anchor grooves being formed at the inner terminals of the flanges and opening into and receding from the said channels, the anchor grooves having their lower portions flush with the upper surfaces of the flanges and the outer and inner channels being connected by cross-channels forming the means of communication between the said channels and grooves.

In testimony whereof we have hereunto set our hands in presence of two subscribing witnesses.

CHARLES C. ALLEN.
CHARLES H. BUSCH.
